SHOE-SEWING MACHINE.

1,114,287.

Specification of Letters Patent.

Patented Oct. 20, 1914.

Application filed June 2, 1911. Serial No. 630,870.

To all whom it may concern:

Be it known that I, EUGENE J. RAY, citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to shoe sewing machines, and more particularly to the type of machines usually designated as McKay sewing machines, which comprise a straight hooked needle and devices coöperating therewith to form a chain stitch, and in which the shoe is supported, during the sewing operation, upon a horn which extends inside of the shoe. In this type of sewing machine the needle is usually threaded by a whirl mounted in the work supporting horn, and it is necessary that the needle remain stationary after its point has entered the horn until its hook is threaded by the whirl and since thicker work necessitates a greater length of thread in the part of the stitch passing through the work, a variable stroke must be imparted to the needle to draw up a loop of thread varying in length with the thickness of the work. The work is engaged between two work engaging members, the horn and a presser foot coöperating therewith, one of which is made movable to accommodate for the varying thicknesses of work, and to insure the proper coöperation of the needle threading mechanism the limit of the needle stroke in the direction of the stationary work engaging member must be fixed, while the limit of the stroke of the needle in the direction of the movable work engaging member must be varied in accordance with the position which the thickness of the work causes the movable work engaging member to assume. The needle must therefore have imparted to it a movement which shall have a dwell while the needle hook is being threaded, and which shall have a limit in one direction varying with the varying thicknesses of the work being sewn. In the commercial type of McKay sewing machine as now usually constructed, such a movement is imparted to the needle by a needle actuating mechanism having a certain amount of lost motion be-

tween two limiting stops. The dwell of the needle while it is being threaded is caused by the lost motion and the variable movement of the needle is caused by having one of the limiting stops under the control of the movable work engaging member so that the limit of the needle stroke when this stop is engaged shall be varied according to the thickness of the work. Such a mechanism has certain disadvantages. To hold the needle at the limit of its stroke to give the necessary dwell, frictional devices must be employed, causing an inevitable loss of power, and the lost motion causes a jerky action of the motion parts and an excessive pounding upon the stops, especially if the machine be run at a comparatively high rate of speed. It has also been proposed to provide for the dwell in the needle motion by actuating the needle mechanism by means of a cam roller running in a cam slot having a dwell formed therein, and to provide for the variable movement of the needle by placing in the link-work or chain of mechanism which transmits the power from the cam to the needle, a slotted member and a pin about which the slotted member turns, the position of the pin in the slot being varied by the movable work engaging member to change the leverage of said member. Such mechanism has the disadvantages that the cam slot and roller are not as good as a crank motion, and that the use of a pin-and-slot connection for imparting the variable movement necessitates both a pivoting and a sliding movement of the slotted member in relation to the pin, which causes a double amount of wear on these parts, and it is impossible to thereby secure as good or as positive a mechanical linkage, especially when the parts have become somewhat worn, as when journaled bearings are employed.

An object of the present invention is to provide an improved mechanism for imparting to the needle a movement having a dwell while the needle hook is being threaded.

The present invention in its broader aspects contemplates the attainment of this object by an arrangement of pivoted points or bearings which shall obviate the employment of cams or lost motion in the parts.

A preferred form of construction for causing the dwell in the needle movement consists in a chain of mechanism for transmit-

ting power to the needle which comprises certain pivotal points so situated therein and having their relative movements so timed that at least one of these points shall 5 have a movement approximately at right angles to the direction in which it transmits its effective motion to actuate the needle so that no motion, or, at most, a very minute amount of motion, shall be transmitted to 10 the needle during the time when it is desired that the dwell shall occur.

Another object of the present invention is to provide an improved mechanism controlled by the thickness of the work for imparting a variable movement to the needle. 15 To impart such variable stroke to the needle, the present invention contemplates the provision of a needle actuating mechanism comprising a series of relatively movable parts 20 and a connection from said mechanism to the work support or presser foot whereby a variation in the thickness of the work being operated upon will adjust said mechanism so as to change the angular relation of the 25 paths of movement of certain of the parts, such change in the angular relation of the paths of movement causing more or less of the movement of one part to be transmitted to another part and thereby causing a variation 30 in the needle stroke. In the preferred form of construction embodying this feature of the invention, the relatively movable parts of the needle actuating mechanism are pivotally connected and the adjustment of 35 the mechanism upon a variation in the thickness of the work being operated upon produces a change in the relative paths of movement of the pivotal connections of the parts.

In the illustrated preferred embodiment 40 of the invention the means for causing the dwell in the needle movement and the means for causing the movement of the needle to be variable, are shown as forming co-operating elements of the mechanism which transmits the power from the driving shaft of the 45 machine to the needle bar, but the present invention contemplates within its scope the employment of either of said means separately or in other combinations than that 50 illustrated.

To prevent the needle hook from catching in the loop of the previously formed stitch when it is retracted through the work, it is usual to provide for the needle a cast-off 55 which covers the needle hook as the needle is withdrawn from the work, and which is drawn back to expose the hook of the needle when the needle enters the work. This cast-off is moved with relation to the needle to 60 perform its function and it is usual to provide yieldable means for pressing the cast-off against the surface of the work to hold the loop of the previous stitch away from the needle, and said yieldable means allows 65 the cast-off to adjust itself for varying thick-

nesses of work. It is found, however, that when the cast-off is pressed against the surface of the work its end will in time become roughened or bent by coming in contact with tacks which are left in the work, and also 70 that when soft work is being sewn the cast-off will be pushed down alongside of the needle, unnecessarily enlarging the mouth of the hole in the work punctured by the needle and wedging over and stretching out 75 the loop of the preceding stitch which lies on the surface of the work.

Another object of the present invention is to provide means to limit the movement of the cast-off toward the work, so that, although it shall hold the loop of the preceding 80 stitch from being caught by the hook of the needle, it will be kept from being pressed against or into the work.

With this object in view the present invention comprises the improved cast-off mechanism hereinafter described, as particularly pointed out in the claims.

The present invention also includes certain other new and useful combinations and 90 arrangements of parts which are hereinafter described in the specification and defined in the claims, and the advantages of which will be apparent to those skilled in the art.

The present invention is illustrated as embodied in the type of shoe sewing machine described with substantial accuracy in the patent to Richardson No. 710,612, October 7th, 1902, upon which it is primarily intended as an improvement, but it is to be understood that the present invention is equally applicable to other types of sewing machines, and may be otherwise embodied without departing from the spirit of the invention.

Referring to the drawings: Figure 1 is a front elevation of the head of the machine; Fig. 2 is a side elevation of the head of the machine showing as much of the mechanism as is essential to the present invention; Fig. 3 is a diagrammatic view of the front of the machine head illustrating the needle in its lowermost position, the position of the presser foot and mechanism actuated thereby being indicated in dotted lines for thick 110 work; and Fig. 4 is a view similar to Fig. 3 illustrating the needle in its raised position.

Referring to the drawings, 1 indicates the work supporting horn, and 2 the movable presser foot co-operating therewith. The 120 presser foot is secured at the lower end of a presser bar 3 which is slidably mounted upon the head of the machine. The upper end of the presser bar is provided with a slot 4 in which is engaged a stud 5 fixed to the frame of the machine, and which regulates the downward limit of the presser foot when no work is in the machine, by its engagement with an adjustable pin 6 projecting into the slot from the upper end of 125

the presser bar. The presser foot is raised from the work by a block 7 which is engaged in a lateral recess 8 formed in the side of the presser bar. The block 7 is pivotally secured at the end of a lever 9 on the forward end of a rock shaft 10 which is loosely mounted to rotate in the machine frame. The rock shaft 10 is normally turned by an adjustable spring 11 to hold the presser foot downwardly. Upon the rear end of the rock shaft 10 is secured a lever arm 12 which carries upon its outer end a segmental plate 13. The plate 13 is arranged to be clamped against the side of a lever 14 by means of a clamping arm 15 which is bored to loosely receive a pin 16 projecting from the lever 14 whose enlarged head 17 acts as a fulcrum for the clamping arm 15. The lower end of the arm 15 bears a pin 18 which slides freely through a hole bored in the lever 14 and whose outer end is engaged by a lever 19. The lever 19 is pivoted to the frame and is oscillated by a cam roll 20 running against a cam surface cut on the side of the cam wheel 21 carried upon the shaft 22 of the machine. The cam-actuated lever 19 thus serves to lock the segmental plate 13 against the lever 14 which is oscillated by a cam roll 23 actuated by a cam wheel 24 to raise the presser foot. The presser foot is also adapted to be raised for the insertion or removal of the work by the engagement under the arm 9 of a treadle operated lever 25. The construction and mode of operation of the above mentioned mechanism for raising and locking the presser foot is substantially the same as that described in the patent to Richardson, and further description thereof is deemed unnecessary here, it being sufficient to state that, when the needle is being raised, the presser foot is locked and lifted slightly to raise the work from the horn to allow the stitch to be drawn between the work and the horn, and after the stitch has been set and the work fed, the presser foot is released and is free to adjust itself against the work under the action of the spring 11 in preparation for the next stitch forming operation.

50 The work is fed by means of an awl 26 carried by an awl holder 27 which is pivotally secured at 28 to a plate 29 which is slidably secured to the back of the presser bar. The upper end of the plate 29 is bifurcated to receive a headed pin 30 projecting rearwardly from the presser bar, and the lower end of the plate 29 is slotted to receive a headed pin 31 projecting rearwardly from the presser bar. The awl holder 27 is free to turn about the pivot 28 during the reverse lateral movement of the awl, but is held from turning during the lateral feeding movement of the awl by a rearwardly projecting pin 32 which is engaged by a stop shoulder 33 on the edge of the plate 29. A

spring 34 normally holds the pin 32 against the stop shoulder and also tends to draw the plate 29 to the right to hold the awl in a retracted position. The feeding movement is imparted to the awl by a link 35 which is pivoted at 28 to the plate 29 and whose other end is pivotally secured at 36 to a downwardly extending lever arm 37. The lever arm 37 is secured to the forward end of a rock shaft 38 upon whose rear end is secured a lever arm 39 which bears a cam roll 40 engaging against the face of a cam wheel 41. The rock shaft 38 is normally turned by an adjustable spring 42 to hold the cam roll 40 against the cam wheel and to hold the awl 26 in its retracted position. The cam wheel 41 positively oscillates the rock shaft 38 and draws the sliding plate 29 positively downwardly and to the left to cause the awl 26 to feed the work. The above described awl feed is the substantial equivalent in structure and mode of operation of that disclosed in the Richardson patent.

The thread is drawn through the work and set in a chain stitch by a straight needle 43 whose hook is threaded by a suitable thread handling mechanism in the horn 1. The needle 43 is secured to the lower end of the needle bar 44 which is mounted to freely slide in the machine frame. The needle bar 44 has clamped thereto a collar 45 to which is pivotally secured at 46 a link 47 whose other end is pivotally secured at 48 to one end of a lever 49 whose oscillation reciprocates the needle. The other end of the lever 49 is pivoted at 50 to one end of a link 51, the point 50 forming a swinging fulcrum for the lever 49. The other end of the link 51 is pivotally secured at 52 to one arm of a bell crank lever 53 which is fulcrumed at 54 by a pivot pin 55 journaled in a bracket 56 projecting laterally from the machine frame. The other end of the bell crank lever 53 is pivotally secured at 57 to the lower end of a link 58 whose upper end is pivotally secured at 59 to a pin projecting from the presser bar 3. It will be evident from the above description that the position of the pivot point 52 about the fulcrum 54 will be dependent upon the position of the presser foot. The pin which forms the pivot point 59 is rigidly clamped in a slot 59^a in the presser bar 3 which provides for its longitudinal adjustment thereon to properly position the point 59 in making preliminary adjustments of the machine.

At the point 60 near the middle of the lever 49 is formed a common pivotal connection between the lever 49, the end of an arm 61, and the end of a link 62. The arm 61 is pivoted at 63 by a pin 64 journaled in the machine frame, and the point 60 is thus constrained to move in the arc of a circle about 63 as a center. The power which oscillates the arm 61 is applied to the point 60 by

a reciprocation of the link 62 which receives its reciprocatory motion from the oscillation of a straight lever 65, to one end of which the upper end of the link 62 is pivotally secured at 66. The lever 65 has a swinging fulcrum 67 where it is pivotally secured to the lower end of a link 68 whose upper end is pivotally connected at 69 to a bracket 70 formed upon the machine frame. The other end of the lever 65 is pivotally secured to a crank pin 71 projecting from a plate 72 carried upon the forward end of the shaft 22. The power applied by the crank pin 71 will turn the lever 65 about its fulcrum and communicate the power through the link 62, which will move the pivot point 60 about the center 63. The motion of the point 60 will oscillate the lever 49 about its swinging fulcrum 50 and will impart a positive movement to the needle bar. It will be noticed that in the above described link-work which transmits the motion from the driving-shaft to the needle, all of the connecting points are formed with journaled bearings, that no sliding connections are employed, and that the entire motion is positive.

The desired dwell in the needle motion is secured by an arrangement of the centers 66, 67 and crank pin 71 with relation to each other and to the centers 60 and 69, and the axis of the machine shaft 22. The crank pin 71 moves in an arc whose radius of curvature is the distance between the crank pin and the axis of the shaft and the point 67 moves in an arc whose radius of curvature is the length of the link 68. When the crank pin 71 is in its lowest position (corresponding to the lower limit of the needle stroke), and is moving through the portions of its path which are but slightly inclined to the lever bar 65, the lever will receive a longitudinal movement and at the same time a slight oscillatory movement. Since the crank pin 71 is moving on an arc of a shorter radius of curvature than the fulcrum point 67, the component of the movement of the crank pin 71 at right angles to the lever bar 65 will be greater than the component of movement of the point 67 at right angles to the lever bar. Hence, when the crank pin 71 is moving in the neighborhood of its lowest position, the point 66 will be moved in a curved path which is nearly horizontal, and which is convex upwardly. The radii of curvature of the paths of the crank pin and point 67 are so proportioned, and the crank pin and point 67 are so spaced on the lever 65, that the curve through which the point 66 is moved will have a center substantially coincident with the point 60, so that when the crank pin is moving through its lowest position the point 66 will be swung around the center 60 and the driving shaft will impart no appreciable amount of motion to the needle. This arrangement causes the con-

necting point 66 which is continuously moved by the rotation of the driving shaft to have a portion of its path of movement at right angles to the axis of the link 62, the thrust along the axis of this link being the only component of the movement of the connecting point 66 which is effective in moving the needle bar. The needle is thus caused to dwell or remain practically stationary while its hook is being threaded by the thread handling mechanism in the shoe supporting horn. When the crank pin 71 is near its uppermost position (corresponding to the upward limit of the needle stroke) and moving substantially parallel to the lever bar 65, another dwell will be caused in the needle motion. The relative movements of the points 66, 67 and crank pin 71 is such that the length of this dwell is a great deal shorter than that of the dwell while the needle is being threaded, since the dwell at the upper limit of the needle stroke is not absolutely essential, but is, however, desirable in causing the needle to hold the upwardly drawn stitch loop under tension for a short time.

By suitably laying out the paths of movement of the points 66, 67 and crank pin 71, the lengths of the dwell imparted to the needle at each extremity of its stroke may be varied within certain limits. With the arrangement of these parts as illustrated, the needle has no appreciable movement for about 100° of the rotation of the machine shaft when the needle is at the downward limit of its stroke, and the needle has no appreciable movement for about 10° of the rotation of the machine shaft when it is at the upper limit of its stroke.

Referring more particularly to the diagrammatic views in Figs. 3 and 4, it will be seen that when the needle bar is in its lowermost position as illustrated in Fig. 3, the pivotal points or centers 50 and 54 are co-axial. The position of the presser foot when a comparatively thin piece of work 73 is being sewn is shown in full lines in Fig. 3, while the position of the parts when a comparatively thick piece of work 74 is being sewn is indicated by dotted lines. Since the centers 50 and 54 are co-axial, any motion of the presser bar which turns the bell crank lever 53 about the center 54 will merely turn the link 51 about the co-axial center 50 and will not affect the position of the needle. Thus at its lowermost position the needle will be unaffected by the position of the presser bar and the needle will always have a fixed downward limit for its work penetrating stroke independently of the thickness of the work. When, however, the needle bar is raised from its lowermost position, since the position of the point 60 is constrained to move in an arc about the pivot 63, the center 50 will be swung downwardly and to the left of the center 54. The

relative positions of the parts when the needle bar is raised are illustrated diagrammatically in Fig. 4, the position of the parts when the presser bar is raised by a greater thickness of work being indicated in dotted lines. The centers 50 and 54 are no longer co-axial, and when the point 52 is raised by an upward movement of the presser bar it will act through the link 51 to raise the center 50 and turn the lever 49 about the point 60 to raise the needle bar. It will thus be seen that the uppermost position of the needle is variable according to the position of the presser foot. In the foregoing description the movement of the needle in response to the movement of the presser foot has been shown, it being assumed for the purpose of clearness of description that the chain of needle-actuating mechanism connected to the crank pin 71 was not being moved.

If the presser foot is stationary and the needle mechanism is moved by the crank pin 71, it is apparent that the downward movement of the needle stroke will be the same whatever the position of the presser foot may be, since at the downward limit of the needle stroke the configuration of the parts is such that the center 50 will always be moved into a co-axial relation with the center 54. When, however, the needle is moved up from its lowermost position, the distance of its upward movement will be dependent on the position of the presser foot. Since the point 60 at which the power is applied to the lever 49 is constrained to move in the arc of a circle about 63, and the fulcrum point 50 of the lever 49 is hung by the link 51 to swing about the pivot pin 52, it will be apparent that the amount of motion imparted by the power delivering end of the lever 49 to the needle bar will be dependent upon the relative movements of the point 60 at which the power is applied and the swinging fulcrum 50. When the presser foot is on a comparatively thin piece of work and the point 60 is moved downwardly, the fulcrum 50 will swing downwardly and to the right about the pivot 52 and the needle bar will be raised to the position indicated by the full lines in Fig. 4. When, however, the presser foot is engaging a thicker piece of work, the pivot point 52 assumes a higher position and one nearer to the arc of movement of the point 60, so that when the point 60 is moved downwardly the fulcrum point 50 is constrained to swing less in a downward and more in a horizontal direction, and moves in a path more nearly at right angles to the path of the point 60 and the component of the motion of the fulcrum 50 which is parallel to the direction of movement of the point 60 is less than when the presser foot is upon a thin piece of work, and the power delivering end of the lever

49 will impart a higher lifting stroke to the needle bar, as indicated in the dotted lines in Fig. 4.

While the points 50 and 60 are illustrated in the preferred construction as being constrained in their movement by means of pivoted links, it is evident that such constrained movement might be otherwise provided.

The relative arrangement of the centers in 75 the link-work is preferably such that the needle will always move the same distance from the upper surface of the work, the added amount of movement given to the stroke of the needle being equal to the added 80 thickness of the work being sewn. In practice it is often found desirable to have the loop drawn up by the needle increased in length slightly more than the increase in thickness of the work. Such provision for 85 causing the needle to draw up a loop whose added length is increased more rapidly than the increase in thickness of the work may be readily had by slightly changing the proportions of the lever 53 to change the position of the point 52 about the pivot 54.

The cast-off 75 is slidably held in a longitudinal recess formed along the side of the needle bar and bears at its upper end a block 76. The block 76 extends across to the 95 presser bar and has a spline formed upon one end which engages in a slot 77 cut in the side of the presser bar. A pin 78 extends across this slot and is vertically adjustable in a slot 79 cut through the presser bar. 100 The downward movement of the cast-off is limited by the engagement of the block 76 with the pin 78. The block 76 is bored to slidably receive a rod 80 which bears upon its lower end a collar 81. The rod 80 is 105 loosely received through a bore 82 in the collar 45 on the needle bar, and extends upwardly and slides freely through a bearing 83 in the machine frame. The upper end of the bar 80 is connected by twin links 84 to an arm 85 which is provided near its pivotal point 86 with a frictional device controlled by an adjustable spring 87. This frictional device will keep the bar 80 from 110 movement except as it is positively actuated. The bar 80 receives its movement from the collar 45 which strikes against two stop collars 88 and 89 adjustably secured to the rod respectively above and below the 115 collar. A spring 90 acting between the stop collar 89 and the block 76 keeps the block 76 pressed down against the collar 81. When the needle bar rises, the frictional device holds down the bar 80 and causes the 120 cast-off 75 to lag behind the needle until the needle hook is drawn beneath and is covered by the cast-off. The collar 45 then engages the stop 88 and the needle and the cast-off are moved up together. When the 125 130

needle bar descends, the cast-off is held up by the frictional device and the needle descends and enters the work with its hook freed from the cast-off. After the needle 5 has entered the work, the collar 45 engages the stop 89 and moves the rod 80 together with its collar 81 downwardly. Since the block 76 is held upwardly only by the block 81, it is moved down by the spring 90 until 10 the block 76 engages against the pin 78 on the presser bar, which limits its downward movement. The downward motion of the bar 80 is sufficient so that the limit of the downward movement of the cast-off will be 15 controlled entirely by the position of the presser bar. The pin 78 is preferably adjusted in the presser bar so that the cast-off shall come sufficiently close to the work to prevent the loop of the previously formed 20 stitch from being drawn between the cast-off and the work, but yet be kept from actual contact with the work, so that its end cannot be marred by tacks in the work. If, 25 however, it is desired that the cast-off come into contact with the work, but be prevented from following the needle down into the work, the pin 78 can be adjusted to arrest the movement of the cast-off as soon as it 30 has come in contact with the work but prevent its penetration into the work. Since the presser foot 2 is in contact with the upper surface of the work, the position of the cast-off will always be the same with 35 relation to the surface of the work irrespective of its thickness.

The operation of the various parts of the machine illustrated in the drawings and above described have been indicated in the 40 description already given, and will be readily understood by those skilled in the art.

The invention having thus been described, what is claimed is:

1. A shoe sewing machine, having, in combination, a needle, mechanism for actuating the needle comprising a series of relatively movable parts pivotally connected to allow only a relative turning movement between the connected parts, a work support, a 45 presser foot, and a connection to said mechanism acting upon a change in the relative position of the presser foot and work support to change the angular relation of the 50 paths of movement of the parts of said mechanism to vary the needle stroke, substantially as described.

2. A shoe sewing machine, having, in combination, a needle, mechanism for actuating the needle comprising a series of relatively 55 movable parts pivotally connected to allow only a relative turning movement between the connected parts, a work support, a presser foot, and a connection to said mechanism acting, upon a change in the relative

position of the presser foot and work support, to change the relative paths of movement of the pivotal connections of said mechanism to vary the needle stroke, substantially as described. 70

3. A shoe sewing machine, having, in combination, a needle, mechanism for actuating the needle comprising a series of relatively movable levers and links pivotally connected to allow only a relative turning movement 75 between the connected elements, a presser foot, a work support, and a connection to said mechanism acting, upon a change in the relative position of the presser foot and work support, to swing one end of one of said links about a center relatively movable with relation to the pivot at the other end of the link but co-axial therewith at one limit of the needle stroke to vary the other limit of the needle stroke, substantially as described. 80

4. A shoe sewing machine, having, in combination, a needle, mechanism for actuating the needle comprising an oscillating arm, a lever pivotally mounted on said arm, a connection between one end of the lever and the needle, a link connected to the other end of the lever, a support to which the link is pivotally connected, a presser foot, a work support, and a connection to the link support acting upon a change in the relative position of the presser foot and work support to move the link support to vary the needle stroke, substantially as described. 90

5. A shoe sewing machine, having, in combination, a needle, mechanism for actuating the needle comprising an oscillating arm, a lever pivotally mounted on said arm, a connection between one end of the lever and the needle, means engaging the other end of the lever to swing the lever on its pivot during the oscillation of the arm, and a presser foot and suitable connections acting upon a change in the position of the presser foot to vary the oscillation of the lever and thereby vary the needle stroke, substantially as described. 10

6. A shoe sewing machine, having, in combination, a needle, mechanism for actuating the needle comprising an oscillating arm, a member pivotally mounted on the arm to have only a turning movement relative thereto, a link support, a link pivotally connected at one end to said support and at the other end to said member, a presser foot, a work support, and a connection to said link support operating upon a change in the relative position of the work support and presser foot to move the link support and thereby change the path of movement of the pivotal connection between the link and member to vary the needle stroke, substantially as described. 11

7. A shoe sewing machine, having, in combination, a needle, mechanism for actuating

- the needle comprising a lever, a movable support for the lever, means for moving said support, a connection between one end of the lever and the needle, a link connected 5 to the other end of the lever, a support for the link pivotally mounted upon a center co-axial with the pivotal connection between the lever and the link at one limit of the needle stroke, a presser foot, a work support, and a connection to the link support 10 acting upon a change in the relative position of the presser foot and the work support to move the link support about its pivot and thereby vary the other limit of the needle 15 stroke, substantially as described.
8. A shoe sewing machine, having, in combination, a needle, and mechanism for actuating the needle comprising a continuously rotating crank, a longitudinally moving and 20 oscillating lever pivotally connected at one end to the crank, a link connected to the other end of the lever, connections between said link and the needle, and a swinging supporting link for the fulcrum of said 25 lever co-operating with the crank to move the lever during a substantial portion of its revolution without imparting motion to the needle, substantially as described.
9. A shoe sewing machine, having, in combination, a needle, mechanism for actuating the needle comprising a continuously rotating crank, a longitudinally moving and oscillating lever pivotally connected at one 30 end to the crank, a swinging supporting link 35 for the fulcrum of the lever, an oscillating
- arm, a link connecting the lever and arm, a needle actuating lever pivotally mounted on the arm, a connection between one end of said actuating lever and the needle, a link connected to the other end of the needle actuating lever, a support for said last mentioned link, a presser foot, a work support, and a connection to said link support acting upon a change in the relative position of the work support and presser foot to move said support and thereby vary the needle stroke, substantially as described. 40
10. A shoe sewing machine, having, in combination, a work support, a presser foot movable toward and from the work support, a needle on the same side of the work as the presser foot, a movable cast-off therefor, and a stop connected to the presser foot for causing the movement of the cast-off toward the work to be arrested in a predetermined position with relation to the work, substantially as described. 45
11. A shoe sewing machine, having, in combination, a needle, a cast-off therefor, adapted to be yieldably moved toward the 50 surface of the work, and a limiting stop controlled and positioned by the thickness of the work to arrest the movement of the cast-off at a predetermined position with relation to the work, substantially as described. 55
